DESIGN FOR A TISSUE SHEET DISPENSER

Alexander C. H. Weiss, Chicago, Ill.

Application July 31, 1946, Serial No. 132,157

Term of patent 7 years

(Cl. D58—12)

To all whom it may concern:

Be it known that I, Alexander C. H. Weiss, a citizen of the United States, residing at Chicago, in the county of Cook and State of Illinois, have invented a new, original, and ornamental Design for a Tissue Sheet Dispenser, of which the following is a specification, reference being had to the accompanying drawing, forming part thereof.

I claim:

The ornamental design for a tissue sheet dispenser, as shown.

ALEXANDER C. H. WEISS.
